Attorney

UNITED STATES PATENT OFFICE.

CLARA FREEMAN, OF PHILADELPHIA, PENNSYLVANIA.

BRASSIÈRE.

Application filed April 14, 1925. Serial No. 23,039.

This invention relates to certain improvements in brassières; and the nature and objects of the invention will be readily recognized and understood by those skilled in the arts involved in the light of the following explanation and detailed description of the accompanying drawings illustrating what I at present consider to be the preferred embodiments or mechanical expressions of the invention from among various other forms, arrangements, combinations and constructions of which the invention is capable within the spirit and scope thereof.

With the types of brassières in general use for confining and securing the bust, the figure is objectionably thickened and made to appear stouter because the bust is forced together in front and results in an elevation or bulge at the front center portion of the figure. Such brassières by forcing the bust together at the front center of the body further tend to throw and redistribute the weight of the bust to unnatural points of the body, so that the natural freedom of movement and grace of carriage are interfered with. Forcing and binding the bust together frequently causes chafing and irritation of the skin, particularly in warm weather, and instead of adding to the comfort and health of the wearer, tends to detract therefrom by unduly binding and applying pressures to the bust and preventing ease and freedom of movement and natural respiration.

One of the main objects of the present invention is to provide for the practical elimination of the tendency of brassières to draw the bust together and centrally elevate or bulge the bust with the resulting unnatural thickening and deformation of the figure, by so arranging and constructing a brassière that the bust is separated and supported thereby in such a manner as to tend to flatten the figure and give the same the appearance of having natural well formed lines.

A further object of the invention resides in arranging a brassière so as to prevent chafing of the bust and to so support the bust that the weight is distributed to natural points of the body and the ease of movement and natural grace of carriage preserved, while eliminating undue pressure on the bust and avoiding injury to the health of a wearer.

Another object of the invention is to provide a brassière having a bust supporting and

separating band so designed and arranged as to prevent unnatural bulging of the bust and to secure a natural appearance for the figure.

Another object of the invention is to provide a bust supporting and separating band for brassières which is adapted for and capable of attachment to and mounting on various types of brassières, either as an element of a brassière when manufactured, or added to a complete brassière.

A further object of the invention is to provide a brassière having a bust separating and supporting band, with an arrangement for adjusting the brassière to vary the pressure exerted thereby, so as to permit of altering the style or type of figure effect produced by the brassière.

With the foregoing general objects, and certain other objects and results in view, which other objects and results will be readily understood by those skilled in the art from the following explanation, the invention consists in certain novel features in construction and in combination and arrangement of parts, as will be more fully and particularly referred to and specified hereinafter.

Referring to the accompanying drawings, in which similar reference characters designate corresponding parts throughout:

Fig. 1, is a view, more or less diagrammatical, of a portion of the body and bust, showing a brassière embodying the invention in position for attachment on and around the body and bust, with an arrangement of snap fasteners for adjustably securing the brassière in position around the body.

Fig. 2, is a front view of a brassière of the invention in applied, attached position on the body, and showing the bust supporting and separating band in dotted lines in operative relation with respect to the bust.

Fig. 3, is a rear view of the brassière applied in mounted position on the body, with the brassière unfastened to show the bust supporting and separating band in attached position.

Fig. 4, is a view of the inner side of the brassière in open, unapplied position, with the bust supporting and separating band attached to the upper central portion of the inner side thereof.

Fig. 5, is a detailed view of the rear, free

ends of the brassière and bust supporting and separating band, showing an arrangement of fasteners of the hook and eye type for adjustably attaching the brassière around the body.

One possible embodiment and adaptation of the features of the invention, is illustrated in the accompanying drawings as applied to a brassière of the conventional type, but it is to be understood that the invention is not limited to the type of brassière disclosed, as it is capable of application to and use with brassières of various other types, as well as similar garments for encircling and securing the bust. The illustrated embodiment and application thereof, are presented purely by way of example and not of limitation, for purposes of explanation to bring out the principles and features of the invention so that those skilled in the art can readily understand the same.

In the accompanying drawings a brassière 10 is disclosed as indicative of such types of garments generally, and in the present instance embodies a relatively wide band-like length of material for encircling the body and bust of a wearer, in the usual manner familiar in this art. The brassière 10 is provided with the usual shoulder straps 11, and is open at the back or rear side thereof, the free end edge portions 12 and 14 being provided with suitable securing or fastening elements 15 arranged in vertically aligned rows therealong, as will be readily understood. In use, the brassière 10 is placed in position around and encircling the body and bust, as shown in Figs. 2 and 3, and is fastened in position at the back by the hereinbefore securing elements 15, in the usual manner, so that the brassière covers and confines the bust under pressure. However, in position applied to the body, the bust is forced inwardly toward the central portion of the body over the diaphragm which causes the objectionable bulge or elevation of the bust and unnatural thickening of the body, as hereinbefore referred to.

According to the invention and in the mechanical expression thereof presented herewith, referring now particularly to Fig. 4 of the drawings, a band or strip of material 20, preferably of fabric and if desired formed with the usual elastic inserts (not shown), although not so limited, is attached at its central portion to the upper central portion of the inner side of the brassière 10, and disposed in position longitudinally of the brassière. In this instance the band 20 is attached to brassière 10 by the stitching 22 although if desired the attachment of band 20 may be by separable fasteners or the like of the usual or any other desired types well known in the art. The major portions or lengths of the band 20 are unattached to the brassière 10, as will

be clear by reference to the accompanying drawings, and the opposite free ends 21 of the band 20 are formed with suitable attaching and fastening means 23, in the present instance embodying suitable buttons on one of the ends 21 and button holes on the other end 21 for receiving the same.

By another feature of the invention the brassière 10 is formed for adjustable fastening around the body so that the degree of pressure exerted on the body and bust by the brassière can be varied, to meet the needs or desires of the wearer. This feature of the invention is illustrated in detail by Fig. 5 of the drawings, and embodies the provision of parallel, spaced rows of vertically aligned eyes 16 on one end 12 of the brassière, and a single row of vertically aligned hooks 17 on the opposite end 14 of the brassière for selective engagement with either of the rows of eyes 16. As the rows of eyes 16 are spaced inwardly from each other, it will be readily apparent that by securing hooks 17 to the inner row of eyes 16, a tighter fit around the body with greater pressure is secured, while fastening hooks 17 in the outer row a looser fit and less pressure is obtained, which will be more fully explained hereinafter. In the example illustrated by Fig. 5, fasteners of the hook and eye type are disclosed but it is not intended to limit this feature of the invention thereby, as any other desired or suitable type of separable fastening means can be employed, such for example as the snap type diagrammatically indicated by the fasteners 15 of Figs. 1 and 3, and the button type 15' of Fig. 4.

A brassière 10 having the band 20 of the invention attached thereon, is applied to the body as indicated in Fig. 1 of the drawings, with the straps 11 over and supporting the brassière from the shoulders and the front of the brassière over the bust, with the attached portion of band 20 located and disposed between the upper portions of the breasts. The free unattached lengths of the band 20 are passed under the breasts and rearwardly around the body, where they are fastened together by the fastening means 23, as clearly shown in Fig. 3 of the drawings in particular. After the bust supporting and separating band is attached the brassière 10 is then passed around the body over band 20 and fastened together at the rear by the fastening means 15. The band 20 in attached position draws the front central portion of the brassière inwardly against the body, between and separating the breasts, as will be clear by reference to Fig. 2 of the drawings, and this tends to move the breasts outwardly toward the shoulders, with the resulting flattening of the bust, while at the same time depressing the central portion of the brassière and giving the bust a natural, well formed appearance.

The position of band 20 under the bust supports the same and by separating and moving the breasts slightly outwardly the natural tendency of the wearer is to 5 straighten the shoulders and hold a more correct carriage. By the foregoing positioning of the bust the weight thereof is more naturally distributed and the ease and comfort of the wearer increased, while the 10 separation of the breasts eliminates objectional chafing and irritation with resulting benefit to the health. The bust supporting and separating band 20 also does away with undue and injurious pressures on the bust 15 by supporting the same in a more natural position.

With the brassière 10 provided with the fastening means arranged as shown in Fig. 5, the figure effect can be varied in cooperation 20 with the band 20, as by raising the bust slightly and attaching the brassière ends together in the tightened position, the bust can be maintained through the aid of band 20, in such position, while by using the outer 25 rows of fastening means the bust can be lowered to give a flat figure effect. Due to the position of the band 20 in attached position, with the brassière extending thereover, the bust is maintained against displacement 30 at all times and under all conditions. It will here be noted that the ends of the brassière with the attaching or fastening means thereon can be formed and arranged to lie at the side of the body instead of the 35 back if found desirable or expedient.

The bust supporting and separating band can be attached to and supplied with and as an element of a brassière when manufactured, or can be manufactured and furnished 40 separately for attachment to brassières by the users, and the invention contemplates and includes the band in either attached position or as a separate article for attachment to a brassière or the like.

While in the example of the invention presented herewith, the band 20 is shown as attached to the brassière by stitching or the like, it is not intended to so limit the invention, as the band 20 can be attached in 50 operative position on and relation with respect to a brassière by loosely attaching the same thereto; for example, by passing the band through slits or openings in or formed on the brassière. Further, in the embodiment 55 hereof a single band is employed, but the invention contemplates and includes the use of a plurality of bands where desired or found expedient.

It is also evident that various changes, 60 modifications, variations and substitutions might be resorted to without departing from the spirit and scope of my invention, and hence I do not wish to limit myself to the exact disclosures hereof.

Desiring to project my invention in the

broadest manner legally possible, what I claim and desire to secure by Letters Patent of the United States, is:

1. In combination, a brassière, and a bust supporting and separating body encircling 70 band attached to the front portion of the brassière between the bust portions of the latter and free from said brassière at the sides of the bust portions, the attached portion of the band and brassière when in worn 75 position disposed between and separating the bust with the band in position around the body and between the body and bust, and the brassière in position around the body and over the bust.

2. In combination, a brassière having a closed front, and a bust supporting and separating band attached intermediate its ends to the central portion of the closed front of the brassière, the opposite lengths of the 85 band free from the brassière throughout the major portion of their lengths for extending around the body and between the body and bust.

3. In combination, a brassière having a 90 closed front, and a bust supporting and separating body encircling band attached to the closed front of the brassière between the bust portions of the latter and free from the brassière at the sides of the bust portions, 95 and means for securing the band in position around the body and between the body and the bust with the attached portion between the busts to draw the front portion of the brassière against the body between and 100 separating the busts.

4. In combination, a brassière, and a bust supporting and separating body encircling band attached to the front of the brassière between the bust portion of the latter, the 105 band providing opposite lengths for extending around the body and between the body and the bust for supporting the latter, and means for securing the opposite lengths of the band around the body with the portion 110 of the brassière attached to the band drawn between and separating the busts.

5. In combination, a brassière, and a bust supporting and separating body encircling band providing straps attached at their 115 inner ends to the front central portion of the brassière between the bust portions thereof, said straps free from the brassière throughout their lengths, and means for securing the free ends of the straps together 120 with the band formed thereby extending around the body and between the body and the bust and the front central portion of the brassière attached thereto drawn thereby between and separating the busts.

6. In combination, a brassière, means for adjustably fastening the brassière around the body and over and across the bust to permit of varying the pressure exerted by 130 the brassière on the bust, and a bust sup-

porting and separating body encircling band attached to the front of the brassière between the bust portions of the latter and free from said brassière at the sides of the bust portions, the attached portion of the band and brassière in worn position disposed between and separating the busts with the band in position around the body and be- tween the body and busts, and means for securing the opposite lengths of the band together with the band around and encircling the body.

Signed at Philadelphia, Pennsylvania, this 11th day of April 1925.

CLARA FREEMAN.
